UNITED STATES PATENT OFFICE.

PERCY J. CALLOWHILL, OF PROVIDENCE, RHODE ISLAND, ASSIGNOR TO THEODORE W. FOSTER & BRO. COMPANY, OF PROVIDENCE, RHODE ISLAND.

DESIGN FOR A MIRROR OR SIMILAR ARTICLE.

Application filed April 4, 1925. Serial No. 13,023. Term of patent 3½ years.

To all whom it may concern:

Be it known that I, Percy J. Callowhill, a citizen of the United States, residing at Providence, in the county of Providence and State of Rhode Island, have invented new, original, and ornamental Design for a Mirror or Similar Article, of which the following is a specification, reference being had to the accompanying drawings, forming part thereof.

The drawing is a view of a mirror or similar article.

I claim:

The ornamental design for a mirror or similar article, as shown.

In testimony whereof I have signed my name to this specification in the presence of two subscribing witnesses.

PERCY J. CALLOWHILL.

Witnesses:

S. N. McCCLARENCE,
J. A. MILLER.
